(57) **CLAIM**

The ornamental design for a portable charging electronic device, substantially as shown and described.

DESCRIPTION

FIG. 1 is a front elevation view of a portable charging electronic device, according to a first embodiment of my new design;

FIG. 2 is a rear elevation view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a front elevation view a portable charging electronic device, according to a second embodiment of my new design;

FIG. 8 is a rear elevation view thereof;

FIG. 9 is a left side elevation view thereof;

FIG. 10 is a right side elevation view thereof;

FIG. 11 is a bottom plan view thereof; and,

FIG. 12 is a top plan view thereof.

The broken lines in the drawings illustrate environmental subject matter that forms no part of the claimed design.
